UNITED STATES PATENT OFFICE

ALFRED BARTLETT SMITH AND CLIFFORD ROSS SMITH, OF WOLVERHAMPTON,
ENGLAND

MIXING APPARATUS

Application filed September 24, 1927, Serial No. 221,677, and in Great Britain October 5, 1926.

Our invention relates to a method and means for mixing pulverulent or granular materials and/or for mixing or blending such materials with liquids or with semi-solid substances.

The invention is more particularly intended for mixing sand with oil, compounds, clays, or other binding materials, for core-making and other foundry purposes, but is capable of a wider use in mixing operations, as for example in mixing sand or crushed chippings or slag with bituminous materials for road making and like purposes, or in dough mixing, clay preparation and similar operations.

15 The object of the invention is to obtain an efficient coating or blending of the individual grains of the sand or other material with the binding agent or other ingredient of the admixture.

20 The invention primarily consists in the method of mixing and blending the materials by the co-operation of inclined or curved moving and fixed, or relatively moving, members, in a suitable apparatus, which carry the material and throw and roll it about the container and in addition squeeze it in wedge-like pockets or passages formed by the co-operating members, eventually shearing the mass therein.

25 As a result of this action, after only a relatively short treatment every particle of the materials is dealt with individually, and, in the case of blending powdered or granular materials with liquids or semi-solids, an even distribution of the liquid or semi-solid is effected and the particles or grains of the material under treatment are fully and completely coated.

30 The invention also comprises apparatus for carrying out the method, in which sweeps or blades act in conjunction with pressure surfaces, either fixed or relatively moving, so that the materials are squeezed between the 35 sweeps and pressure surfaces.

A further preferred feature of the invention is the provision of means in the apparatus to toss or throw the materials, after the squeezing action, to break up the mass and facilitate intimate mixing.

35 In order that the invention may be readily understood, it will be hereafter described as applied by way of example to a horizontal pan type mixer by the aid of the appended drawings.

40 Figure 1 is a plan of this apparatus.

45 Figure 2 is a vertical section thereof.

50 Figure 3 is a detail section shewing a discharge door.

55 Figure 4 is a plan of a fixed pressure member or plate.

60 Figures 5 to 10 are sections of the plate taken on lines correspondingly numbered in Figure 4.

65 Figure 11 is a plan of one of the rotating sweeps, and

70 Figures 12 and 13 are sections thereof on lines 12-12, and 13-13 of Figure 11.

75 In the illustrated, and preferred, form of apparatus for carrying out the method, a stationary pan *a* of suitable dimensions is employed, which may be open at its upper end, and has at a suitable point at or near its circumference a discharge opening *b* in its base arranged near the periphery of the pan and controlled by a suitably operable slide or shutter *c*.

80 The edge of the discharge opening is preferably backwardly inclined and the door oppositely inclined to render the device self cleaning as far as possible and prevent choking with sand or the like. The upper edges of the opening and door are slightly bevelled as shewn in Figures 3, as this we find assists in making a sand tight closure. A vertical shaft or revoluble sleeve *d* arranged axially of the pan, and driven in any suitable manner, as for example by worm and worm wheel from the driving shaft *e*, carries a series of horizontal blades or sweeps *f*.

85 Each sweep *f* is arranged to form 90

at its leading edge or face a suitable angle with the base of the pan and being inclined rearwardly in the direction of motion of the shaft or sleeve *d*. Arranged above the upper 5 edge of the shaft or sleeve *d*, and rotatable therewith, is a distributing dome or spreader *g* for the materials as the latter are charged into the pan.

The moving blades or sweeps *f* are disposed in the lower part of the pan, so that 10 their forward lower edges rotate just clear of the pan base, and they are preferably set to incline or curve backwardly from the true radial line. The action of these sweeps, therefore, is to press forward and raise the material from the base of the pan until it climbs 15 and rolls over the elevated rear or trailing edges, and at the same time, by reason of the angle at which the sweeps are set, they tend to throw or force the material radially outwards towards the circumferential wall of 20 the pan.

In the upper part of the pan *a*, there are secured to the circumferential wall, and extending inwardly therefrom, a series of fixed 25 pressure surfaces in the form of blades or plates *h* of novel formation. The "entrance" edges of these plates, which are first encountered by the material as it is carried round by the action of the moving blades, 30 are the highest, and as the exit ends are approached, the under surfaces of the plates gradually lower and preferably also approach the centre sleeve or shaft *d* until they 35 terminate in a horizontal plane lying at a slightly higher level than the plane in which the rear or trailing edges of the sweeps rotate.

The entrance edge is preferably curved 40 backwardly as it approaches the centre of the apparatus to tend to turn materials impinging on it inward toward the centre.

The under, and operative, face of each 45 fixed blade or plate, is preferably composed of two or more inclines or curves, a more abrupt inclined face *i* near the entrance edge giving way to a more gradual wedging face *j* toward the exit edge. The particular shape of the blades in the present example is shown 50 by a series of sections, Figs. 5 to 10.

In the apparatus so far made by us, these blades or plates have been cast hollow with a curved top surface to shed or deflect, into the pan, any material falling on it.

As the material is thrown outwards by the sweeps it is turned over upwardly and inwardly by the fixed blades or plates, and by contact with the pan wall in a substantially spiral manner, and as a sweep approaches the 55 horizontal lower edge of a plate it tends to force the material into, and through, a space of gradually diminishing area, constituted by the sloping face of the fixed plate and the pan base, thus exerting a powerful squeezing 60 action.

When mixing sand with oil or compound, the mixture begins to form a "bond", or to stiffen, as the particles of sand become coated, and while the materials at first appear to be thrown outwardly and returned in a spiral direction to be squeezed and then tossed over the rotary sweep, as a "bond" or complete mixture takes place, the materials seem to rise in masses or chunks over the rotary sweep and to drop over the back of the sweep and break up, giving a further mixing action.

The combination of movements thus given to, and of the actions exerted upon, the material by the co-operation of the sweeps and fixed blades, produces a very intimate admixture and blending.

In mixing sand with oils, clays, or binding compounds for foundry purposes, an intimate and even admixture is essential if the requisite "bond" is to be obtained, and we have been able to achieve the desired results in our improved apparatus in a rapid and economical manner.

Although the particular embodiment above described constitutes a good practical form 90 of the invention, it will be apparent that modifications may be made.

In one arrangement, both the plates and the sweeps may revolve, in different directions and at similar or suitably proportionate 95 speeds. In another arrangement, we may rotate the pan carrying the plates, the sweeps being stationary.

It will be apparent that the means employed to drive the moving part, or parts, as 100 the case may be, of the apparatus, may vary in many ways from the particular driving arrangement illustrated.

Similarly, any suitable means, operable either by hand or power, may be provided 105 in place of the screw actuated discharge slide *c* to open and close the discharge opening at the desired times, and more than one discharge opening may be provided if desired. If necessary, a pivoted striker may be provided in the wall of the pan adjacent the discharge opening to break up any material adhering to the sweeps as discharge takes place.

We claim:—

1. Apparatus for mixing finely divided materials with a binder, comprising a cylindrical container, a spindle rotatable about a vertical axis in the centre of the container, a domed distributing member above the centre of the container, backwardly raked and inclined blades carried by and rotating with the spindle and extending substantially from it to the inner face of the container, fixed members extending from the inner face of the container substantially to the spindle and provided with pressure surfaces forwardly curved towards the wall of the container and downwardly inclined from their leading edges, the said surfaces becoming in- 115 120 125 130

creasingly close to and co-operating with the rotating blades to form squeezing pockets without lateral escape, and means for discharging the mixed materials from the container.

2. Apparatus for mixing finely divided materials with a binder, comprising a cylindrical container, means for discharging mixed materials from the container, a spindle 5 rotatable about an axis in the centre of the container, backwardly raked and upwardly inclined blades carried by and rotating with the spindle and extending from it approximately to the inner face of the container, 10 fixed members having forwardly curved and downwardly inclined pressure surfaces secured to the side walls of the container and extending inwardly approximately to the spindle, the upper edges of the blades being 15 arranged so that they just clear the lower edges of the pressure surfaces and the blades as they rotate co-operating with the pressure surfaces to form wedge-like pockets between them in which the materials in the container 20 are squeezed with progressive pressure without opportunity for lateral escape as they are carried around by the blades.

3. Apparatus for mixing finely divided materials with a binder, comprising a cylindrical 25 container, a spindle rotatable about an axis in the centre of the container, blades carried by the spindle and extended into close proximity to the inner wall of the container and rearwardly raked and upwardly inclined from 30 their leading edges to their rear edges and adapted to thrust materials in the container upwardly and work them away from the centre, fixed members extending substantially 35 from the inner face of the container to the 40 spindle and having surfaces adjacent to and co-operating with the rotating blades, these surfaces being inclined downwardly and away from the edge which first meets the materials and adapted to press the materials 45 downwardly and towards the centre of the container under progressive pressure and without lateral escape, and means for discharging the mixed materials from the container.

4. Apparatus for mixing finely divided materials with a binder, comprising a cylindrical container, a spindle rotatable about an axis in the centre of the container, backwardly raked and inclined blades carried by 50 and rotating with the spindle and extending from the spindle substantially to the inner wall of the container, fixed pressure members carried by the inner face of the container and extending into close proximity to the spindle, and being forwardly curved towards the wall of the container and downwardly inclined from their leading edges, the said members being above, closely adjacent to and co-operating with the rotating 55 blades and presenting first an abrupt and

then a gradually inclined under surface toward the blades, whereby the materials may be first forced to pass up and fall over the blades and then to be squeezed between the blades and the approaching pressure surfaces without opportunity for lateral escape, and means for discharging the mixed materials from the container.
